UNITED STATES PATENT OFFICE.

PATRICK REILLY, OF MATTOON, ILLINOIS.

AIR-BRAKE FOR CARS AND LOCOMOTIVES.

SPECIFICATION forming part of Letters Patent No. 290,269, dated December 18, 1883.

Application filed October 19, 1883. (No model.)

To all whom it may concern:

Be it known that I, PATRICK REILLY, a citizen of the United States, residing at Mattoon, in the county of Coles and State of Illinois, 5 have invented a new and useful Improvement in Air-Brakes for Cars and Locomotives, of which the following, in connection with the annexed drawings and letters of reference marked thereon, is a specification.

10 My invention relates to an improvement in automatic air-brakes, the same being specially applicable to the construction known as the "Westinghouse automatic air-brake," for which Letters Patent were granted April 13, 15 1869; but it is not limited thereto, as it may be applied advantageously to other analogous air-brakes.

It consists in the combination, with an automatic air-brake, of an additional line of pipe 20 having a suitable cock or cocks, the said line of pipe serving as a safety-exhaust from the auxiliary reservoirs in case of an emergency, and being applied under the train of cars, connected with the auxiliary air-reservoirs provided with the usual pipe-couplings, and extended up to the cab of the engineer, so that the engineer has immediate control thereof; and its object is to provide for the exhaustion of 25 all the air through the auxiliary reservoirs 30 and said additional line of pipe whenever the brakes become "set" from accidental causes—as, for instance, from a hose breaking, pipe leaking, or otherwise—and thus effecting an instantaneouse release of all the brakes, and 35 preventing very serious damage or loss of life in times of accident, or in an emergency when it is all important that the brakes shall all be set free without a moment's delay.

In operating with the Westinghouse air-brake it is found that if it becomes set from any of the above-mentioned causes the brake-shoes remain fixed upon the wheels and the train cannot be moved until the train-men get under the cars and allow the air to escape from 45 the reservoirs, and this causes delay to the train, which, with the passenger-trains, is quite an item, and, more important, it often results in serious accidents.

In the accompanying drawings, Figure 1 is 50 a bottom view of a car provided with my invention and such parts of a Westinghouse brake as are necessary to aid in the elucidation

of the same; and Fig. 2 is a bottom view of a "tender" and the rear portion of a locomotive, showing my invention and parts of the said 55 air-brake. The wheels, trucks, brake-shoes, and other portions of the train, being unnecessary, are omitted in the drawings.

A represents a car, B a tender, and C the rear portion of a locomotive, all inverted. 60

D is the air-supply pipe of the Westinghouse air-brake, connecting the auxiliary air-reservoirs E of the car and tender with the main air-reservoir F on the locomotive.

G are the brake-cylinders, operating the 65 brakes as described in the Westinghouse patent, and connected with their respective reservoirs E by means of pipes g, provided with three-way operating-cocks e, by means of which the air is admitted to or exhausted from the 70 brake-cylinders; and g' are housings of springs employed for forcing the pistons back, in order to release the brakes.

H is my exhaust line of pipe, connected, as at m, with the reservoirs E by hollow T-joints, 75 or other suitable means, and having its sections coupled between the cars and tender of a train by means of suitable couplings, h, similar to those commonly used on air-pipes of air-brakes. Suitable cocks, h', are provided near 80 the ends of the cars, or in the couplings, in order to close the continuous line of pipe H at the end of a train, and thus prevent a constant blowing off of the compressed air from the reservoirs E. The pipe H is extended to 85 the "engineer's cab" or platform e of the locomotive C, where it is provided with a cock, h², within convenient reach of the engineer. This cock h² serves as the means for allowing 90 the air from the reservoirs E and the other parts connected therewith to escape into the open atmosphere when it is necessary to suddenly release the brakes. The pipe H may be turned up and fastened to the breast-plate of the locomotive-boiler, and the cock h² may be 95 attached to it at such height as to enable the engineer to distinctly hear the air escaping from it, and thus serve as an indicator of the fact that the brake is in operative condition for releasing the brake-shoes.

It will be understood that the engineer shuts off the air-supply of the reservoirs E before he opens the cock h²; and also that the air-brake as now constructed, and to which my 100

invention is added, will be provided with all the appliances used for controlling and manipulating it.

What I claim as my invention, and desire to secure by Letters Patent, is—

1. The combination, with an air-brake, of the exhaust line of pipe H, with the auxiliary reservoirs E, substantially as and for the purpose described.

2. The combination, with the air-reservoirs of an air-brake, of a supply-pipe, D, and an air-exhaust pipe, H, both under the immediate control of the engineer, substantially as and for the purpose described.

3. The combination, with an air-brake, of 15 a relief means whereby all the air may instantaneously be exhausted from the auxiliary reservoirs by the operation of a cock under the control of the engineer and from the engine-platform, substantially as and for the purpose described.

PATRICK REILLY.
